UNITED STATES PATENT OFFICE.

THOMAS W. BERRY, OF DORCHESTER, MASSACHUSETTS.

SOLE-LEATHER ROLLER.

Application filed January 19, 1921. Serial No. 438,495.

To all whom it may concern:

Be it known that I, THOMAS W. BERRY, a citizen of the United States, residing at Dorchester, in the county of Suffolk and 5 State of Massachusetts, have invented a new and useful Sole-Leather Roller, of which the following is a specification.

This invention relates to winding drums and has for an object to facilitate in tightly 10 fastening the materials to be wound on the drums and to facilitate in removing such materials when wound.

Another object of this invention is to provide a device of this character especially 15 adapted to operate with drums used in winding leather, textiles and the like into rolls, and to provide a binding strip and means for clamping it tightly over the material to be wound thus holding the material 20 securely to the drum during the operation of winding.

Another object of the invention is to provide means to insure the even winding of the materials into rolls and which will prevent 25 wrinkling and uneven stretching and tearing or other injury to the material.

The invention consists of the matters hereinafter set forth and claimed and will be fully understood from the following description of the construction illustrated in 30 the accompanying drawings.

In these drawings:

Figure 1 is a side elevation showing the winding drum with material in place to be 35 wound and the binding strip clamped in place over the material.

Figure 2 is a longitudinal sectional view of Figure 1, the parts remaining in elevation.

Figure 3 is a cross section of Figure 1 on the line 3—3.

Figure 4 is an end view showing the clamping member in place over the binding strip.

Referring to the drawings, the numeral 1 designates a winding drum provided in one end with a slot 7. The numeral 3 designates a binding strip of flexible and resili- 45 ent substance with one end notched or bifur-

cated as shown at 9. Numeral 2 designates the material in position to be wound into a roll. Numeral 4 designates a socket at

tached to the drum 1 and adapted to receive one end of the binding strip 3. A clamping member 5 is mounted in the slot 7 of the winding drum 1 by the pivot 6, and is provided with oppositely extending lateral lugs 8, adapted to fit over and engage the furcations of the notched end 9 of the binding strip 3 which is forced down to fit under the lugs 8 and is held tightly in place.

The operation of the device thus described is as follows.

The material 2 is first laid evenly on the drum 1. The end of the binding strip 3 is then inserted in the socket 4 and the strip is laid parallel to the axis of the drum 1 over the material 2. The flexible notched end 9 of the strip 3 is then pressed down to allow it to fit under the lugs 8 of the clamping member 5 which is swung on its pivot 6 to fit over the notched end 9 of the strip 3. The wedging action of the lugs 8 on the end 9 of the strip 3 preserves an even pressure on the material throughout the length of the strip 3. By swinging the clamping member 5 more or less as desired the space between strip 3 and drum 2 may be increased or decreased to fit varying thicknesses of materials.

I claim as my invention:

In a device of the class described, a winding drum having a slot extending transversely of one end and a clamping latch member pivotally mounted in said slot and adapted to project at its free end beyond the perimeter of the drum, a keeper mounted on said drum at the end opposite that having the latch, a strip having one end inserted under said keeper and its other end bifurcated and adapted to extend beyond said slot, said latch member being adapted to be swung between the furcations of said strip and having laterally extending lugs to overlie the furcations of said strip and hold the latter in operative position.

In testimony that I claim the foregoing as my own, I have hereto affixed my signature in the presence of two witnesses.

THOMAS W. BERRY.
